UNITED STATES PATENT OFFICE.

WILLIAM L. ROWELL, OF EAST MILTON, MASSACHUSETTS, ASSIGNOR TO LANSTON MONOTYPE MACHINE COMPANY, OF PHILADELPHIA, PENNSYLVANIA, A CORPORATION OF VIRGINIA.

SEVERING MECHANISM FOR STRIP ELEMENTS OF PRINTING-FORMS.

1,283,922.

Specification of Letters Patent.

Patented Nov. 5, 1918.

Application filed March 1, 1917. Serial No. 151,749.

To all whom it may concern:

Be it known that I, WILLIAM L. ROWELL, a citizen of the United States, and a resident of East Milton, State of Massachusetts, have invented certain new and useful Improvements in Severing Mechanism for Strip Elements of Printing-Forms; and I do hereby declare the following to be a full, clear, and exact description of the same, reference being had to the accompanying drawings, forming a part of this specification.

My invention relates to severing mechanism for cutting in desired lengths strip material such, for instance, as that produced by the commercial machine known as the Monotype lead and rule caster now being made and marketed by the Lanston Monotype Machine Company, such machine being generally similar to that shown and described in U. S. Patent No. 625,998 granted to J. Sellers Bancroft, May 30th, 1899, but modified and adapted for the casting of leads, rules, etc., the novel features of such modifications and adaptations being set forth in the patent to Amos L. Knight No. 1,222,415, dated April 10th, 1917.

A severing device has been applied to the said lead and rule caster in the commercial field, such device being clearly set forth by the Patent No. 1,193,344 of J. Sellers Bancroft and Mauritz C. Indahl, dated August 1st, 1916. The strip casting machine casts type metal in contact with a previously cast portion of the strip in such manner as to cause the two to fuse together, and then advances the fused portions to allow of a subsequent cast being made in contact with the now solidified cast immediately preceding, this process of intermittent casting and advancing of the strip being repeated continuously. The patented severing device is operated by power connections with the driving mechanism of the casting machine, but controlled by the strip produced thereby, in such wise that the shearing mechanism for severing the strip operates when the strip is at rest. The present invention is designed to overcome certain objections to the shearing action of the patented device by employing a rotary cutter, such as a saw, driven preferably from an independent source controlled by the strip itself and properly timed with respect to the move-

ments of the strip, the supporting guides 55 and the pusher.

The invention will now be clearly set forth in connection with the following description of the apparatus shown in the accompanying drawings, illustrating the device of Patent #1,193,344, above mentioned, altered in accordance with the present invention, in which drawings—

Figure 1 is a front elevation of a portion of the apparatus embodying the present invention, the view point corresponding with that of Fig. 1^a of the patent.

Fig. 2 is a sectional elevation looking toward the left in Fig. 1 and

Fig. 3 is a somewhat similar view enlarged, but omitting the motor, the supporting guides, the pusher and associated parts.

It is not necessary to describe in detail the apparatus shown, but it is sufficient to identify some of the parts of the known mechanism and then explain wherein it has been altered to produce the device of this invention.

The strip cast in the mold of the casting machine and intermittently advanced toward the severing mechanism is shown in Fig. 1 by the character 10 (employing the characters of the patent for the parts therein disclosed). This strip as it advances comes before the cutter and then extends beyond the cutter between supporting guides 55 and 55^a. The latter are in the form of bars arranged above the guideway 19 and are carried by hangers 56 and 56^a depending from a horizontal shaft 57. The guideway 19 is supported from the bar 17 by means of the brackets 18. When the end of the strip has struck against the adjustable trip 31 it carries said trip along with it during any subsequent movement before the cutting action takes place; and this trip 31 being secured to the slidable gage rod 26 to which is also attached the slidable cutting elements, such subsequent movement of the strip will maintain the cutting elements and the trip at the distance set and thus not interfere with the accurate cutting of the strip. The movement of the trip, the rod 26 and the cutting elements causes a tilting of the lever 43, as will be more particularly set forth hereinafter, sufficient to operate the escapement pawl device 44 and 45 and thus allow, in the manner of the

patent, the bolt 49 (see Fig. 2) to move upward and the interponent 42 to move outward into the path of movement of the operating lever 14. When the parts are thus 5 positioned, the operating lever on its downward stroke strikes against the interponent 42 and swings the bell-crank lever 39 so as to operate the lever 35, which carries the cutting elements, against the tension of the 10 spring 38. This severing operation takes place while the strip is at rest. The patented mechanism also provides for the swinging of the guides 55 and 55^a substantially in one with the movement of the cutter where- 15 by the strip is cut and transferred laterally substantially simultaneously. This movement is accompanied by an additional movement of the front guide 55 independently of the back guide 55^a so as to allow the severed 20 strip to fall upon the receiving table (not shown). During the forward movement of the cutter the lugs or projections 62^a of the stacker or pusher 62 are rocked in a back- 25 ward direction by the rocking of the pusher 62 through the intermediary of the lever arm 66 and the rod 67 connected with the bell crank 39. Upon the return movement 30 of the cutter the packing lugs are adapted to move forwardly to stack the last strip 35 into contact with those previously cut.

The present invention involves the employment of a rotary cutter and necessitates alterations such as will produce a proper timing of the parts as outlined above, and 35 such changes will now be set forth. The lever 35 carries a circular saw 80 rotatably mounted on the shaft 36 and the upper end of said lever may be pivoted at a higher point than in the patented structure in order 40 to provide for a greater throw of the cutter. As shown this pivot point is provided by the shaft 81 in proximity to the bar 17. The saw is attached to a pulley 82 over which a belt 83 is adapted to run, said 45 belt receiving its power from the pulley 84 mounted on the shaft of the electric motor 85, the latter being supported by brackets 86 extending upwardly from and secured to the bar 17. The pulley 82 is provided with an 50 annular groove 87 into which extends the cutter shifter 88 attached to the gage rod 26. This cutter shifter 88 has its pulley engaging faces extending parallel to the plane of rotation of the pulley (see Fig. 3) 55 and forms a connection between the gage rod and the pulley such that the latter, though free to rotate under the influence of the motor and to oscillate on the center 81, must partake of the longitudinal movements 60 of the gage rod. The cutter shifter 88 is provided with a connection with the sliding frame 89 (to be presently described) this connection being bent around the saw and pulley as shown, so as not to interfere with 65 their action. The sliding frame 89 takes

the place of the cutter frame of the patent, being slidably mounted in the grooves provided for the mounting of the said cutter frame. The saw 80 is designed to operate close to the forward end of the frame 89 70 so that the strips will be properly guided in and laterally held by the frame during the cutting action. This frame is provided with a laterally extending lug 90 against which bears the upper end of the lever 43 seated 75 at its lower end between the escapement pawls 44 and 45.

The saw and pulley being slightly displaced to the right (Fig. 1) with respect to the shear of the patent made it necessary 80 to move a little to the right the hangers 56 and 56^a near the cutter. This is clearly shown in Fig. 1. The shaft 36 is extended to the right (Fig. 1) so that its end is behind the rear guide 55^a. At this location a 85 projection 91 is attached to the shaft, the end of which projection is adapted to bear against said guide or its hanger 56^a when the cutter has been moved forwardly sufficiently to complete the cutting of the strip. The 90 shaft 57 is pinned or keyed to the front hangers 56, by the pin 92, the rear hangers 56^a being loosely pivoted thereon. The end of the shaft 57 near the cutter is provided with a radial projection 93 secured to the 95 shaft for coöperation with the upper end of the lever 61 pivoted also on the shaft 36 and having its lower end extending to contact with the pusher shaft 62 at about the time substantially when the projection 91 100 has caused the lateral movement of the severed strip beyond the guideway 19 as will now be explained. When the strip has just been severed the projection 91 will have come into contact with the hanger 56^a so that 105 a continuance of the forward movement of the cutter will cause the simultaneous forward movement of the hanger 56^a, the guide 56, the severed strip, the hanger 55^a and the 110 guide 55 to move the severed strip over the edge of the guideway 19. In the meantime the lower end of the lever 61 will have come into contact with the pusher shaft 62 and the upper end into contact with the projection 93, following which said lever will 115 move the projection 93 and with it the shaft 57, the front hangers 56 and the front guides 55 at a greater speed, as will readily be seen, than these parts are moved by the projection 91. Accordingly after the part 91 120 has cleared the strip from the guideway 19 the lever 61 and projection 93 will move the guide 55 away from the strip so that the latter will be free to escape.

The operation of the device is similar to 125 that of the patent except as has been seen, that the saw advances to cut the strip completely before the guides 55 and 55^a are moved, the lost motion construction of the projection 91 and of the lever 61 and the 130

coöperating parts causing the guides 55 and 55^a to move forward together holding the severed strip between them immediately after the saw has severed the strip and while 5 the saw is still moving forwardly. The front guide 55 is thereupon moved forwardly at a faster rate than the movement of the other parts, thus allowing the strip to drop from between the guides and fall on the 10 table. Resistance to movement of the hangers 56 and 56^a is provided by the springs 58 and 59 respectively, one end of each of which springs is secured to a pin 59^a fastened to the bracket 18 and the other ends 15 of which springs are secured to the hangers 56 and 56^a.

While the saw is being moved forwardly the packer shaft 62 and lugs 62^a are being rocked backwardly to remove the lugs from 20 the path of the strip when it has been released and falls. Upon withdrawing the saw, the various parts will assume, as will be readily noted, their normal positions, the lugs 62^a in rocking forwardly accomplishing 25 the stacking of the last severed strip against the previously severed one.

I claim:—

1. In mechanism for severing strip elements of printing forms, the combination of 30 the following instrumentalities, to-wit, a longitudinally movable strip guide and a transversely movable strip guide, said guides being spaced from each other, a rotary cutter 35 movable in unison with said longitudinally movable guide and movable transversely with relation thereto in the space between the said guides, a motor for rotating said cutter, means for moving the cutter transversely while allowing it to rotate and 40 a gage interposed in the path of the strip for controlling the longitudinal position of the cutter and longitudinally movable guide.

2. In mechanism for severing strip elements of printing forms, the combination of 45 a rotary cutter mounted to move both longitudinally and transversely of its axis of rotation, means for rotating said cutter in any longitudinal position of adjustment, a gage connected with the cutter for controlling its

position longitudinally of its axis, said gage 50 being adjustably mounted in the path of the end of the strip, supporting guides for the strip intermediate the cutter and gage, means including a cutter supporting lever for moving the cutter transversely of its 55 axis to sever the strip and operative connections between the cutter supporting lever and the guides, said connections being longitudinally located intermediate the cutter and the gage, for moving said guides to release the strip after the cutter has advanced to sever the strip. 60

3. In mechanism for severing strip elements of printing forms, the combination of a rotary cutter mounted to move longitudinally of its axis of rotation, means for rotating said cutter while allowing it to move longitudinally of its axis, a gage connected with the cutter but allowing rotation thereof, said gage being adjustably mounted in 70 the path of the end of the strip, supporting guides for the strip intermediate the cutter and the gage, means including a cutter supporting lever for moving the cutter transversely of its axis to sever the strip, and 75 means carried by said cutter supporting lever and having a lost motion connection with said supporting guides for moving the supporting guides subsequently to the severing of the strip. 80

4. In mechanism for severing strip elements of printing forms, the combination of a rotatable saw mounted to slide lengthwise of the strip and movable transversely thereof to sever the same, a gage adjustably 85 mounted in the path of the end of the strip, a sliding guide one end of which is in proximity to the transverse path of the saw, means for connecting said gage and said sliding guide, means for connecting said 90 gage and said saw while allowing rotation and transverse movement of the latter, supporting guides for the strip between the saw and the gage and an independent motor for rotating the saw while allowing longitudinal 95 and transverse movements of the same.

WILLIAM L. ROWELL.
